UNITED STATES PATENT OFFICE.

ELMER L. SCHUMACHER, OF SOUTHBIDGE, AND WILLIAM H. BOUTELLE, OF STURBRIDGE, MASSACHUSETTS, ASSIGNEES TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,410,274.

Specification of Letters Patent. Patented Mar. 21, 1922.

Application filed June 7, 1921. Serial No. 475,576.

To all whom it may concern:

Be it known that we, ELMER L. SCHUMACHER and WILLIAM H. BOUTELLE, citizens of the United States, residing at 5 Southbridge and Sturbridge, respectively, in the county of Worcester and State of Massachusetts, have invented certain new and useful Improvements in Ophthalmic Mountings, of which the following is a specification.

10

This invention relates to improvements in ophthalmic mountings, being a continuation in part of our application filed December 8, 1920, Serial Number 429,183.

15 The principal object of the present invention is the provision of an improved type of composition or non-metallic frame which shall present a neat, novel and ornamental appearance, forming an improvement over 20 anything previously known in this respect.

A further object of the present invention is the provision of a construction in which the parts shall be so united as to reduce the normal pupillary width of frames 25 of this character, rendering the mounting more satisfactory both from a viewpoint of appearance and from a point of undesirable lateral projections and furthermore in which concealed or inconspicuous metallic 30 bracing members shall be provided to prevent expansion or displacement of the bent temple engaging lugs which render the reduced width of the frame possible.

Another object of the invention is the 35 provision of a mounting in which the temple front shall be of smooth and unbroken form, and in which the hinged joints for the frame shall be disposed in inconspicuous position concealed when the mounting is 40 viewed from the front, and unsightly lateral projections affording hinge connections or attachments shall be eliminated.

Other objects and advantages of our improved construction should be readily apparent by reference to the following specification taken in connection with the accompanying drawings, and it will be understood that we may make any modifications in the specific details of construction shown 50 and described within the scope of the appended claims without departing from or exceeding the spirit of the invention.

Figure I represents a front view of a mounting embodying our improvements.

Figure II represents a view partially in 55 plan and partially in section illustrative thereof.

Figure III represents a fragmentary side view of our improved construction.

Figure IV represents a horizontal sec- 60 tional view of a slightly different embodiment from that particularly illustrated in connection with Figure II.

In the drawings, the numeral 1 designates a bridge or nose engaging portion of 65 an ophthalmic mounting, and the numeral 2 the lens receiving frames or eyes. These parts have been illustrated as formed from composition or non-metallic material, such as xylonite, shell, or the like. As is par- 70 ticularly brought out in connection with the original application of which this is a division, the bridge and lens frames are preferably formed from separate parts of material and adjustably connected as by the 75 metal loops 3, particularly illustrated in Figure II. This, however, forms no part of our present invention, since if desired the bridge and lens receiving frames may be formed from a single piece of material. 80

In frames of this type, that is, the heavy shell or xylonite form, prior to our invention it has been customary to form the eyes with laterally extending lugs of appreciable size, preferably split so that the temple 85 might be hinged therebetween. This construction has laterally extended the temples considerably beyond the edge of the lenses and contrary to the usual principles fol- 90 lowed in frame fitting, in which the temples are disposed as near as possible up to the lenses and are then found to most satisfactorily comply with the requirements of the average face. These lugs, however, have been unsightly, have increased the over all 95 size of the frame, have formed projections liable to catch on the hair or clothing of the wearer and cause the glasses to become broken, and interfere with the general utility and desirability of the frame. 100

In carrying out our invention in place of making use of such laterally extending lugs, we form the frame with slight lug portions 12, which in place of projecting laterally are rearwardly curved, as clearly brought out in Figure II of the drawings. 105 This rearward curving forms a substantially concealed space as at 13 to receive the

hinge plate 14, preferably secured to the front at two or more points, as by the rivets or securing devices 6 and 7, one of which is secured to the front of the frame near 5 the lens receiving groove, and the other near the terminus of the lug.

The advantage of this form of attachment is that the hinge plate itself is curved to conform to the shape of the inner face of 10 the lug and when so attached serves to hold the lug in its curved position and prevent any straining or flattening out of the same under varying climatic or other conditions. A second hinge plate or portion 15 is suitably hinged to the first member and connected to the temple 16. With this form of construction the hinge is concealed from view when the mounting is on the face and substantially concealed when the mounting 20 is folded, the lug folding around and having its terminus in such position that the temple forms a substantially rearward continuation thereof and the end of the heavy temple in no wise shows from the front.

25 In Figure IV we have shown another form of our invention, in which the curved plate 21 is secured to the lug portion 12 of the frame and serves to carry the cap members 22 having the groove 23 in which rides 30 the plate 24 carried by the second hinged section 25 on the temple 26. This plate portion 24 is of arcuate form to slide around in the groove, thus forming a connection in which there is no turning movement on the 35 screw 27. We have found this hinge very satisfactory as causing the temple end to butt against the lug 12 and prevent liability of loosening of the securing screw as the temple is moved.

40 We claim:

1. An ophthalmic mounting including a non-metallic front for the mounting having integral rearwardly curving end-piece portions and a curved metallic bracing member secured to each of said end-piece portions to prevent straightening thereof.
- 45 2. An ophthalmic mounting having a non-metallic lens receiving portion formed with

a rearwardly curving end-piece lug and a metal hinge member having a curved portion 50 inter-engaged with the lug to prevent accidental straightening thereof.

3. An ophthalmic mounting including a non-metallic rearwardly curving end-piece lug and a metal hinge member associated 55 therewith having a curved portion inter-engaged with the lug to prevent accidental straightening thereof, said metallic member terminating in a pivot eye, and a temple pivotally secured to the eye and forming 60 substantially a continuation of the rearwardly curving lug.

4. An ophthalmic mounting including a non-metallic lens receiving frame having a rearwardly curving lug integral therewith 65 and a metallic fitting for the mounting having a curved portion interiorly fitting and secured to the lug and adjacent lens receiving frame to retain the parts in angularly disposed relation.

5. A combination frame including a rearwardly curving composition end piece lug, a co-extensive curved metal attaching portion carried by the lug and holding the same in curved position, and a projecting pivot 75 eye carried by said metal member.

6. A device of the character described including composition lens receiving frames having rearwardly curving composition lugs at the outer sides thereof and metallic hinge 80 connections in the form of plate like members having their greater width corresponding to that of the lugs, said plate like members having curved portions interengaged with the lugs to retain the lugs in their 85 curved position, and having temple pivot connections, the plates being so disposed as to be invisible when the mounting is viewed from the front.

In testimony whereof we have affixed our 90 signatures, in presence of two witnesses.

E. L. SCHUMACHER
W. H. BOUTELLE.
